DESIGN FOR A HAT

Bertha Apfel, New York, N. Y.

Application August 23, 1935, Serial No. 58,264

Term of patent 3½ years

To all whom it may concern:

Be it known that I, Bertha Apfel, a citizen of the United States, residing at New York, in the county of Westchester and State of New York, have invented a new, original, and ornamental Design for a Hat, of which the following is a specification, reference being had to the accompanying drawing, forming a part thereof.

Fig. 1 is a perspective view of a hat, showing my new design as viewed from the side rear.

Fig. 2 is a back diagrammatic view thereof.
Fig. 3 is a side diagrammatic view thereof.

The characteristic feature of the design resides in the shape of the crown portion.

The stippling in Fig. 1 is for shading only.

I claim:

The ornamental design for a hat, as shown and described.

BERTHA APFEL.
